(57) **CLAIM**

The ornamental design for a portable UV lighting fixture, as shown and described.

DESCRIPTION

FIG. 1 is a front perspective view of a portable UV lighting fixture in accordance with the invention.

FIG. 2 is a front view of the portable UV lighting fixture in accordance with the invention.

FIG. 3 is a rear view of the portable UV lighting fixture in accordance with the invention.

FIG. 4 is a first side view of the portable UV lighting fixture in accordance with the invention.

FIG. 5 is a second side view of the portable UV lighting fixture in accordance with the invention, wherein the second side is opposite the first side.

FIG. 6 is a top view of the portable UV lighting fixture in accordance with the invention; and,

FIG. 7 is a bottom view of the portable UV lighting fixture in accordance with the invention.

The broken lines shown in FIGS. 1-7 of various features of the portable UV lighting fixture are for illustrative purposes only and form no part of the claimed design.
